UNITED STATES PATENT OFFICE.

JOHN REICHERT AND CHARLES S. BEEBE, OF RACINE, WISCONSIN.

TANK-LUG.

No. 865,944.

Specification of Letters Patent.

Patented Sept. 10, 1907.

Application filed March 7, 1903. Serial No. 146,626.

To all whom it may concern:

Be it known that we, JOHN REICHERT and CHARLES S. BEEBE, citizens of the United States, residing at Racine, Racine county, Wisconsin, have invented certain new and useful Improvements in Tank-Lugs; and we do hereby declare the following to be a full, clear, and exact description of the invention, such as will enable others skilled in the art to which it appertains to make and use the same.

10 This invention relates to certain improvements in fastening and coupling devices for uniting the ends of hoops or bands and tightening the same, and the invention is more particularly related to improvements in tank lugs.

15 An object of the invention is to provide an improved tank lug or coupling and tightening device exceedingly simple and durable in construction which can be produced at a low price and to which the band ends can be easily and quickly attached, or detached if need be,

20 without the employment of clamping grips or wedges. Another object of the invention is to provide an improved tank lug exceedingly simple and durable in construction and which can be easily produced at a minimum expense preferably by casting the lug in a single piece without the employment of a core in the mold during the casting operation.

The invention consists in certain novel features in construction, in combinations and in arrangements of parts as more fully and particularly pointed out and

30 described hereinafter.

Referring to the accompanying drawings, showing constructions merely as examples for the purposes of explanation of devices among others within the spirit and scope of the invention;—Figure 1, is a plan view 35 of the coupling and fastening device applied, a portion of a tank being shown in cross section, and portions only of the hoops or bands being shown. Fig. 2, is a detail elevation of one of the tank lugs, castings or heads detached. Fig. 3, is a longitudinal section through 40 one of said lugs or heads and the band end attached thereto, the coupling bolt not being shown. Fig. 4, is a cross section through a head and the band end taken, on a complete head and band, in the plane of the line 4—4, Fig. 3. Fig. 5, is a detail bottom plan view of 45 one of the lugs or heads detached. Fig. 6, is a detail cross section of a lug or head taken in the plane of the dotted line 6—6, Fig. 3. Fig. 7, is a detail longitudinal section through one of the lugs or heads, the band end not being shown, the section being taken in the same 50 plane as that of Fig. 3, the stop being in the form of a continuous bridge piece instead of two fingers as shown in Figs. 2 and 3. Fig. 7^a, is a cross section through the form of lug having the continuous bridge piece, taken in the plane of the line 7^a—7^a, Fig. 7. Fig. 8, is an 55 elevation of a coupling and fastening device differing somewhat in construction from the devices appearing

in preceding views, a portion of the tank being shown in elevation with the band ends united by said coupling and fastening device. Fig. 9, is a longitudinal section through the coupling and fastening device of 60 Fig. 8, a portion of the tank being shown in cross section. Fig. 10, is a cross section through the band and one of the heads or lugs, taken on the plane of the line 10—10, Fig. 9. Fig. 11, is a detail section in the plane of the line 11—11, Fig. 8. Fig. 12, is a detail section 65 of a single coupling bolt lug without the studs and stop fingers of preceding views.

In the drawings 1, is a tank or vessel built up of staves or sections.

2, is a flat metal band encircling said tank and provided with means for fastening its ends and by which the band can be adjusted or tightened around the tank. Said means comprise two heads, lugs or fastenings attached to the band ends and united or connected by one or more coupling and adjusting bolts or rods. 70

Each head, in the specific example shown, is formed in one piece of metal, such as a casting, and comprises a flat base portion 3, having a flat longitudinal seat to receive the flat end portion of the hoop or band and formed with the side or edge stops or walls 4, along the 80 longitudinal side edges of the band end.

The base, along and intermediate the length and breadth of this seat is provided with one or more rigid outwardly projecting pins or studs 5, integral with the base, although all forms of our invention are not 85 limited thereto. These studs can be variously shaped although I show each cylindrical in form.

The head or lug extends longitudinally from the inner end of said seat or base portion usually in the form of an open frame or loop open at the center in inward 90 continuation of said longitudinal seat and formed by the side walls 6, 6, and the upwardly arched inner end or bridge 7, between said side walls and having the opening 8, therethrough for the coupling bolt 9. The coupling bolt or rod 9, extends between the pair of 95 heads and through the openings 8, in the end pieces or bridges, and the nuts 10, 10, on the screw threaded ends of the bolt screw up to and abut against the upper outer faces of said end pieces in drawing the two heads toward each other in tightening and fastening the band. 100

The open frame of each head or lug is recessed as shown to receive the nut 10, and permit free rotation thereof and to permit free access of the wrench or other tool for grasping and turning the nut. The lower edges of the said open frame are formed to seat and bear 105 against the surface of the tank, although usually the inner face or edge of the end piece or bridge is recessed to permit passage thereunder of the projecting end of the band.

We do not wish to so limit the invention to such a recess but the band end may extend from the longitudinal seat of the flat base across the open center of said frame

and under the said end bridge through the recess therein. Also as at present advised, we do not wish to limit the invention to forming the flat base with an inwardly projecting frame to receive the coupling bolt and nut.

5 The band end is adapted to rest flat down on the said seat, and the band is formed with perforations 11, to receive the studs hereinbefore mentioned. These studs are preferably of a length which is greater than the thickness of the band so that the studs will extend 10 through and project a distance beyond the outer face of the band. These holes can be easily formed at the desired points in the length of the band at the locations where the bands are being applied, and it is not necessary that the bands be accurately prepared in the shop 15 for application to each particular tank.

The studs are of sufficient strength to withstand the strain exerted thereon by the bands when tightened, and we provide means to hold the bands down to the seats and against outward movement from or off the studs.

20 For instance, we can provide each head with means located outwardly beyond the inner end of the said seat, to extend over or at the outer face of the band end and prevent outward movement thereof tending to permit the band to slip from the studs or to hold the band 25 down on the seat, or limit movement thereon even though the studs are not employed and the band is otherwise confined to or on the seat. In other words, each head can be formed or provided with one or more rigid stops under which the band end passes to hold the 30 band on the studs.

The stop can be formed by an elevated cross or bridge piece 12 formed integral with the lug, see Figs. 7, 7^a, and arranged transversely thereof to extend completely across the outer face of the band located on the 35 seat of the base. The cross piece 12, is elevated above the plane of the band seat and above an opening therethrough and beyond an end edge thereof, so as to serve as a stop across the outer face of a band on said seat whether said band is secured by the studs or is otherwise 40 coupled to the lug and confined on the seat.

In applying the head or lug, it will be first tilted and slipped onto the band end so that the band passes at an angle between the end of the base and under the stop 12; the lug can then be tilted or rocked to its normal 45 position against the tank which will bring the band against the flat base and the studs projecting through the holes in the band, see Figs. 1 and 3.

If desired, the stop can be in the form of inwardly projecting transverse fingers 13, 13, see Figs. 2, 3, 4, 5, 50 in the same transverse plane as the stop 12, of Fig. 7.

On the second sheet of the drawings, we show the invention adapted to a coupling device employing two parallel coupling bolts 14, 14, with screw threaded ends carrying nuts 15, 15. In this last named construction, the flat base portion, with its seat and studs, is practically the same as previously described, but the open end frame is not employed. Instead of said open end frame, the outer end of the base is provided or formed with the lateral and forwardly extending enlargements or extensions 16, at their outer ends having the upwardly projecting eyes receive the coupling bolts and each formed by the outer web 7, and the inner web 7'.

The stops 18, 18, extend inwardly from said eyes 65 forwardly beyond the front inner end of the said flat

base or seat. These stops perform the same function as in the construction of Sheet 1 and if desired can be in the form of a bridge piece as in Fig. 7.

In Fig. 12, we show the lug formed with the flat base and having the seat 3', with edge stops or walls 4' 70 but having transverse holes 19, to receive bolts or rivets for securing the band to the lug instead of the studs 5, of preceding views. In said Fig. 12 we have also omitted the stops under which the band end slips, as the rivets or bolts passing through the band and lug 75 will hold the band down in its seat.

Each coupling bolt eye, in the various constructions shown, is formed by two arches, cross webs or bridges viz:—an inner web or arch 7' and an outer web or arch 7, and these webs are arranged in different yet adjacent transverse planes. The outer web is arched upwardly or outwardly and at its inner edge is rounded to receive the bolt, and the inner web is rounded or recessed at its outer edge to receive the coupling bolt. The coupling bolt passes under the outer web and over 80 the inner web, but the outer web engages said bolt to one side of the plane of the inner web.

The lug or casting is entirely open beneath the outer web or arch and is entirely open above the inner web or arch. By means of this arrangement in connection 90 with the formation of the base plate and end open frame or side enlargements, each lug can be cast without a core and by the employment of a plain mold and a device of great strength is produced by reason of the peculiar formation of each coupling bolt eye, as well 95 as by the other features in the formation of the lug or casting.

The bands can be readily and quickly applied to the heads or lugs and if desired, the heads can be readily removed from the bands when it is desired to 100 place new bands on a tank.

The devices are exceedingly strong and durable and can be manufactured and sold at a low price, and dispense with the employment of loose or extra grips or clamps.

Having thus fully described our invention, what we claim is:—

1. As an article of manufacture, a tank lug comprising a longitudinal base on which a flat band is adapted to seat, and a coupling bolt eye formed by an inner cross web or bridge portion and an outer cross web or bridge portion arranged adjacent and in different transverse planes, the eye being open above the inner web and below the outer web, substantially as described.

2. As an article of manufacture, a tank lug comprising 115 a flat base on which a flat band is adapted to seat and an open frame extending from one end of the base and at its outer end having a coupling bolt eye formed by two adjacent cross webs arranged in different transverse planes, one of said webs being arched outwardly to pass over a coupling bolt and the other web depressed to pass under said coupling bolt, substantially as described.

3. As an article of manufacture, a tank lug having a base adapted to receive a band and a portion arranged beyond said base and provided with a coupling bolt eye formed by two adjacent cross webs arranged in different transverse planes, one of said webs arched outwardly, and the other web depressed inwardly, said portion being open below and above said webs, respectively, substantially as described.

4. In combination, two tank lugs, and a coupling bolt and its heads or nuts, each lug comprising a flat base adapted to receive a band and provided with means to confine the band thereon and a coupling bolt eye arranged at the end of the lug and formed by an inner transverse 135

web or portion passing under said bolt and an outer transverse web or portion arched outwardly and passing over said bolt in a plane to one side of the plane of said inner web, the outer side face of said outer web forming a bearing seat for a nut or head on said bolt said lug being open above said inner web and below said outer web, substantially as described.

5. A coupling lug formed in one piece and consisting essentially of a longitudinal flat base and an enlarged loop 10 frame extending forwardly and horizontally beyond the front end of said base and comprising opposite longitudinal side members connected at the front end of the lug by a transverse portion forming an elevated coupling bolt eye a distance in advance of the front end of said seat 15 and separated therefrom by the opening between the side members of said frame, said side members provided with rigid transverse stop fingers in advance of the front end of said seat and arranged over the opening of said frame, substantially as described.

20. 6. A tank lug comprising a flat longitudinal base having a rigid stud projecting therefrom and provided with side portions, and a transverse elevated stop device rigid with said portions and arranged beyond the inner end of said base, the lug being open below said device, said lug having a coupling bolt eye at its inner end, and a flat band 25 adapted to fit longitudinally on said base and receive said stud and project beyond the base under said device, substantially as described.

7. A coupling lug formed in one piece and comprising 30 longitudinal opposite side members at the forward end of the lug connected by a transverse portion forming an ele-

vated coupling bolt eye, a longitudinal flat band receiving seat between said side members and terminating a distance in rear of said transverse portion, and a transversely disposed stop device rigid with said side members and beyond an end edge of said seat and elevated above the plane thereof, said lug being open between side members and below said stop device, substantially as described.

8. A coupling lug formed in one piece and consisting essentially of a longitudinal flat base and an enlarged loop 40 frame extending forwardly and horizontally beyond the front end of said base and comprising opposite longitudinal side members connected at the front end of the lug by a transverse portion forming a coupling bolt eye a distance in advance of the front end of said seat and separated therefrom by the opening between the side members of said frame and having its nut engaging face over said opening, said side members provided and formed with rigid transverse elevated stop means in advance of the front end of said seat and arranged over the opening of said 45 frame.

In testimony whereof we affix our signatures, in presence of two witnesses.
